US00D806807S

(12) **United States Design Patent** (10) Patent No.: **US D806,807 S**
(45) Date of Patent: **** Jan. 2, 2018**

(54) **PORTABLE FITNESS EQUIPMENT**

(71) Applicants: **GOLDONEKOREA INC.**, Seoul (KR);
DONG KOO KANG, Gyeonggi-Do (KR)

(72) Inventor: **Dong Koo Kang**, Yangju-si (KR)

(**) Term: **15 Years**

(21) Appl. No.: **35/501,519**

(22) Filed: **Mar. 4, 2016**

(80) **Hague Agreement Data**

Int. Filing Date: **Mar. 4, 2016**

Int. Reg. No.: **DM/091805**

Int. Reg. Date: **Mar. 4, 2016**

Int. Reg. Pub. Date: **Sep. 9, 2016**

(30) **Foreign Application Priority Data**

Jan. 18, 2016 (KR) 30-2016-0002371

(51) **LOC (11) Cl.** **21-02**

(52) **U.S. Cl.**

USPC **D21/672**

(58) **Field of Classification Search**

USPC D21/672, 798, 678, 679

CPC A63B 21/0004; A63B 21/06

See application file for complete search history.
